CLAIM

I claim the ornamental design for a combination helmet and cap, as shown and described.

DESCRIPTION

FIG. 1 is a rear perspective view of a combination helmet and cap, showing my new design, a strap thereof in a fastened configuration;

FIG. 2 is a top plan view thereof;

FIG. 3 is a left-side elevational view thereof, the strap in an unfastened configuration;

FIG. 4 is a rear elevational view of FIG. 3;

FIG. 5 is a right-side elevational view of FIG. 3;

FIG. 6 is a front elevational view of FIG. 3; and,

FIG. 7 is a bottom plan view of FIG. 3.

The broken lines showing a person in FIG. 1 depict environmental matter and form no part of the claimed design.
